UNITED STATES PATENT OFFICE.

EDWIN LUNDGREN, OF FREDERICK, MARYLAND, ASSIGNOR TO COMBUSTION ENGINEERING CORPORATION, OF NEW YORK, N. Y., A CORPORATION OF NEW YORK.

POWER-OPERATED DUMP GRATE.

Application filed October 24, 1922. Serial No. 598,574.

To all whom it may concern:

Be it known that I, EDWIN LUNDGREN, a citizen of the United States, residing at Frederick, county of Frederick, State of Maryland, have invented a certain new and useful Improvement in Power-Operated Dump Grates, of which the following is a full, clear, and exact description.

My invention relates to dump grates and more particularly to power operated dump grates for furnaces of the automatic stoker type, and has for its object to provide a dump grate of this character which is simple, strong and durable in construction, and reliable in operation.

The several features of the invention will be clearly understood from the following description and accompanying drawings, in which,—

20 Figure 1 is a plan view, partly in section, of a power operated dump grate with the dumping member thereof partly broken away, embodying the features of the invention in their preferred form;

25 Fig. 2 is a longitudinal sectional view, partly in elevation, taken on the line 2—2 of Fig. 1;

30 Fig. 3 is a detail sectional view taken on the line 4—4 of Fig. 2; and

35 Fig. 4 is a detail side elevation, partly in section, of a portion of the mechanism illustrated in Fig. 2, but with parts shown in a different position.

40 The power operated dump grate illustrated in the drawings is provided with the usual dumping member 2 which is secured at one end on a rock-shaft 4. As shown one end of the rock-shaft extends through and is journaled in an adjustable bearing block 6, which is mounted on a frame 8 adapted to be secured to a side wall of the furnace. The actuating mechanism for the dumping member comprises an arm 10 having one end secured on the end of the rock-shaft 4 and its other end bifurcated so as to embrace a block 12 mounted on a horizontal piston rod 14 between collars 16 and 18 secured on the rod. The block 12 is held from rotary movement on the rod, but is permitted to slide longitudinally between the collars 16 and 18 by means of a suitable key 20. A latch pawl 22 is pivotally mounted at one end on a pin 24 secured to the supporting frame 8 and its free end is weighted and is provided with a latching shoulder 26 which

is adapted to engage the rear or left-hand face of the block 12, viewing Fig. 2. The extent of the downward movement of the latch-pawl 22 is limited by means of a vertical screw 28 secured thereto which extends through a slot in a bracket 30 secured to the top of the frame 8, the screw being provided with adjustable stop nuts 31 on its upper end that are adapted to engage the top of the bracket 30. The piston rod 14 extends through and is mounted for reciprocation in a bearing block 32 secured to the frame 8 and a bearing 34 in a steam cylinder 36. A piston 38 is secured to the rod and is mounted in the steam cylinder, 70 the cylinder being provided with intake ports 40 and 42 and with exhaust ports 44 and 46. The intake ports are adapted to be alternately opened and closed by means of a valve 48 and the exhaust ports are adapted to be alternately opened and closed by means of a valve 50. The valves 48 and 50 are adapted to be simultaneously actuated by means of a lever 52 pivoted at 54 on the steam cylinder and pivotally connected with a link 58 midway between its ends, the ends of the link being pivotally connected with arms 60 secured to the valve stems.

Upon movement of the piston rod 14 forwardly or toward the right, viewing Fig. 2, the collar 16 by engagement with the rear face of the block 12 will act through the block and the arm 10 to swing the dumping member 2 into its closed or raised position as shown in Fig. 2. As the dumping member reaches its closed position the latch-pawl 22 is permitted to drop by gravity so as to bring its latching shoulder 26 back to the rear face of the block 12, and thus the dumping member is securely held in closed position by the pawl after the tension in the steam cylinder releases. Upon rearward movement of the piston rod 14 the pawl 22 is raised out of engagement with the block 12 as shown in Fig. 4 so as to permit the dumping member to swing open by gravity. To provide for this the collar 18 is rounded over and the under side of the pawl 22 is provided with a roll 62 which is engaged by the rounded or cam surface of the collar 18 to raise the pawl during the first part of the rearward movement of the piston rod. The free end of the latch-pawl 22 is provided with an inclined surface 64 so as to enable the block 110

12 to ride beneath the pawl during the forward movement of the piston.

From the foregoing it will be apparent that upon moving the hand-operated lever 52 downwardly to the position indicated in Fig. 2, the dumping member will be automatically released and permitted to swing open by gravity; and that upon moving the lever 52 upwardly the dumping member 10 will be swung into closed position and securely locked automatically in this position. In case the dumping member should not be swung completely open by gravity after the latch 22 is released and during the rearward movement of the piston rod, the collar 18 will be brought into engagement with the block 12 and act through the block to force the dumping member open.

As will be evident to those skilled in the art my invention permits of various modifications without departing from the spirit thereof or the scope of the appended claims.

What I claim is:

1. A dumping device of the class described for a furnace having, in combination, a pivotally mounted dumping member capable of being swung into and out of closed position, and a reciprocating fluid actuated piston and suitable connections for 25 swinging the dumping member into closed position during the movement of the piston in one direction, for automatically locking the member in said position, and for automatically releasing said member from said 30 connections and permitting it to swing open by gravity upon movement of the piston in the opposite direction.

2. A dumping device of the class described for a furnace having, in combination, a pivotally mounted dumping member capable of being swung into and out of closed position, a reciprocating fluid actuated piston and suitable connections for 40 swinging the dumping member into closed position during the movement of the piston in one direction, a device for locking said member in closed position, and means carried by the piston rod for releasing said device from the dumping member to permit 45 the dumping member to swing open by gravity during the movement of the piston in the opposite direction.

3. A dumping device of the class described for a furnace having, in combination, a pivotally mounted dumping member capable of being swung into and out of closed position, means for operating said member comprising an upwardly projecting arm movable therewith, a reciprocating 55 fluid actuated piston, a piston rod, a block mounted to slide on the rod, a pin and slot connection between the block and the arm, and a stop member carried by the piston rod arranged to engage the block to swing 60 the dumping member into closed position 65

upon movement of the piston in one direction.

4. A dumping device of the class described for a furnace having, in combination, a pivotally mounted dumping member 70 capable of being swung into and out of closed position, means for operating said member comprising an arm, a reciprocating fluid actuated piston, a piston rod, a block mounted to slide on the rod, a pin and slot connection between the block and the arm, and a stop member carried by the piston rod arranged to engage the block to swing the dumping member into closed position upon movement of the piston in one direction, and means acting automatically to hold the block from movement in one direction when said dumping member is swung into closed position so as to lock said member in said position. 80

5. A dumping device of the class described for a furnace having, in combination, a pivotally mounted dumping member capable of being swung into and out of closed position, means for operating the dumping member comprising an arm, a fluid actuated piston, a piston rod, means for swinging the dumping member into closed position comprising a block mounted to slide on the rod, a pin and slot connection between the block and arm, an abutment carried by the rod and arranged to engage the block to swing the dumping member into closed position when the rod is moved in one direction, a latch arranged to engage the block when the dumping member is swung into closed position so as to lock said member in said position, and a member carried by the rod arranged to release the latch from the block when said rod is moved in the opposite direction so as to permit the dumping member to be swung open. 95

6. A dumping device of the class described for a furnace having, in combination, a pivotally mounted dumping member capable of being swung into and out of closed position, means for operating said member comprising an arm, a reciprocating rod, connections between the rod and arm for swinging the dumping member into closed position upon movement of the rod in one direction, means comprising a gravity actuated latch for locking the arm from movement in one direction when the dumping member is swung into closed position so as to lock said member in said position, and means carried by the rod for releasing the latch upon movement of the rod in the opposite direction. 110

7. A dumping device of the class described for a furnace having, in combination, a pivotally mounted dumping member capable of being swung into and out of closed position, means for operating said member 115

comprising an arm, a reciprocating fluid actuated piston, connections between the arm and piston for effecting movement of the dumping member into and out of closed position upon movement of the piston in opposite directions, respectively, and means comprising a gravity actuated and automatically controlled latch for locking said arm from movement in one direction when the dumping member is swung into closed position so as to lock said member in said position.

8. A dumping device of the class described for a furnace having, in combination, a pivotally mounted dumping member capable of being swung into and out of closed position, means for operating said member comprising an arm, a reciprocating fluid actuated piston, connections between the arm and piston for swinging the dumping member into closed position upon movement of the piston in one direction, means comprising a latch acting automatically to lock said arm from movement in one direction when the dumping member is swung into closed position so as to lock said member in said

position, and a member carried by the piston into engagement with the latch during the movement of the piston in the opposite direction so as to release the latch to enable the dumping member to be swung open. 30

9. A dumping device of the class described for a furnace having, in combination, a rock shaft, a dumping member mounted on the rock shaft and capable of being swung by the rock shaft into and out of closed position, an operating arm secured to the rock shaft, a reciprocating fluid actuated piston, connections between the piston and said arm for swinging the dumping member into closed position upon movement of the piston 40 in one direction, a device acting automatically to engage the arm when the dumping member is swung into closed position to lock the member in said position, and means carried by the piston rod for releasing said device from said arm to permit the dumping member to swing open by gravity during the movement of the piston in the opposite direction. 45

EDWIN LUNDGREN.
